UNITED STATES PATENT OFFICE.

WILLIAM F. CLASEN, OF MILWAUKEE, WISCONSIN.

TRAIN-PIPE COUPLING.

1,118,107.

Specification of Letters Patent.

Patented Nov. 24, 1914.

Application filed May 19, 1913. Serial No. 768,413.

To all whom it may concern:

Be it known that I, WILLIAM F. CLASEN, a citizen of the United States, and resident of Milwaukee, in the county of Milwaukee, and State of Wisconsin, have invented new and useful Improvements in Train-Pipe Couplings, of which the following is a description, reference being had to the accompanying drawings, which are a part of this specification.

My invention has relation to improvements in train pipe couplings, and particularly to the class of train pipe couplings wherein metallic coupling pipes are adapted to be substituted for the ordinary hose pipe connections, and consists more particularly in certain improvements upon Letters Patent of the United States issued to me under date of March 2, 1909, No. 913,811.

The primary object of the present improvements is to provide a construction wherein an improved form of connection is employed, whereby the terminal sections of the coupling are united in such manner that said terminal sections will be absolutely prevented from accidental separation due to any turning or vibratory movement occasioned by jars or other causes, to which they may be subjected while the device is coupled or in use between cars, while yet at the same time permitting of the longitudinal separation of said terminal members when the cars are subjected to undue longitudinal stresses due to either accidental or designed uncoupling thereof.

With the above primary, and other incidental, objects in view, the invention consists of the devices and parts, or the equivalents thereof, as hereinafter more fully set forth.

In the accompanying drawings, Figure 1 is a side view of my invention showing it connected to the train pipes of two cars; Fig. 2 is a plan view of the device detached from the cars; Fig. 3 is a longitudinal section of the terminal members of the device, showing said members coupled together, and also showing the spring actuated dogs and their handles, the handle of one of said dogs being shown as partly broken away; Fig. 4 is a side view of the terminal members coupled together; Fig. 5 is a sectional view on the line 5—5 of Fig. 3 through the terminal members of the device; Fig. 6 is a detail view of one of the straight sections of the coupling and one of the elbowed sec-

tions thereof, the straight section being broken away; Fig. 7 is a horizontal section on the line 7—7 of Fig. 6 looking upwardly in the direction of the arrows; and Fig. 8 is a similar section to Fig. 7, but showing a continuous split spring ring for bearing against the outer and inner flanges or flaps of the U-shaped packing, instead of the two split spring rings shown in Fig. 7.

Referring to the drawings, the numerals 9—9 indicate fragments of two cars adapted to be coupled together by ordinary car coupling members 10—10. Depending brackets 11—11 from the cars carry the ordinary train pipes 12—12 of the respective cars, said pipes provided with the usual valves 13—13 whereby the pipes may be closed when the cars are separated.

My improved train pipe coupling consists of two complementary portions and each of said portions consists of a plurality of metallic members, the member which is connected to the train pipe being indicated by the numeral 14, the two next succeeding upper elbows of one coupling member by the numerals 15—15, the next succeeding straight member of each coupling member by the numeral 16, the two next succeeding lower elbows of each coupling member by the numerals 17—17, and the terminal straight member of each coupling section by the numeral 18, the latter being provided at its extremity with a locking head 19. It will be seen, therefore, that each coupling member, besides including the straight members 16 and 18, the locking head 19 and the elbow 14 which connects to the train pipe, also includes two upper elbows 15—15 and two lower elbows 17—17.

The members 14, 15, 16, 17 and 18 are connected by normally inseparable joints, which are arranged, however, to permit relative rotation of the respective members. The construction of these joints is best illustrated in Figs. 6, 7 and 8. From these figures it will be noticed that each end of an elbow member is provided with an enlarged annular head 20 forming an interior seat 21 for an inverted U-shaped packing 22, of leather, or other suitable material. Internally this head is also provided with an annular shoulder 23 upon which rests the lower end of a tube 24, the said tube extending outwardly from the head and being provided with female threads for the engagement therewith of male threads on the

end of the next adjacent elbow member. Intermediate of its length the tube 24 is formed or provided with an annular shoulder 25, which, in conjunction with the seat 21, forms an annular space 26 for the accommodation of the inverted U-shaped packing 22.

For the purpose of holding the head or enlargement 20 in engagement with the tube 24, I employ a clamping ring formed of the sections 27—27 hinged together at 28, and connected together at their opposite ends by means of a removable split pin 29. This hinge connection is clearly shown in Figs. 6, 7 and 8 of the drawings. By withdrawing the pin 29 the sections of the ring can, of course, be swung outwardly out of their clamping engagement.

I employ the inverted U-shaped packing instead of an ordinary packing, in view of the fact that the former forms a much more efficient preventative against leakage at the joint. By its U-shaped form two flaps or wings are necessarily provided, one bearing against the outer wall of the annular space 26 and the other against the inner wall thereof. To insure the best results, however, and to furthermore insure positive bearing and contact of these flaps against the said walls, spring pressure is provided against both the outer and inner flaps. Any desired form of spring pressure may be employed, so long as the spring action is such as to cause spring pressure in opposite directions against the respective flaps. In Fig. 7 I show the spring in the form of two separate and distinct split spring rings, designated by the numerals 30—30, one bearing against the outer flap of the packing and the other against the inner flap thereof, while in Fig. 8 I show a modified form wherein the spring is in the form of a single coiled split spring ring 31, a portion thereof acting against the outer flap and another portion thereof against the inner flap.

By the construction of the joint described, it will be seen that one of the members is capable of rotation freely within the other, and yet leakage is effectually prevented by the employment of the novel form of packing. Also by providing for relative rotation of the members, a substantially universal movement of the terminal sections 18—18 is permitted, since the series of members are so connected as to be permitted to rotate on a plurality of horizontal axes extending at right angles to each other and on one vertical axis.

Fig. 3 of the drawing, taken in connection with Figs. 1, 2, 4 and 5, clearly illustrates the construction of the separable coupling joint between the terminal members 18. Each of the locking heads 19 of the terminal members 18 is provided with a segmental tongue 32, which tongue is provided

at its outer edge and medially thereof with an open-ended slot 33, and each coupling member is also provided with a segmental or arc-shaped projection 34 against which the inner face of the opposed segmental tongue 32 is adapted to bear, when the coupling heads are brought into coupling relation. The inner faces of these arc-shaped projections are also on a bevel, and the opposed faces of the segmental tongues are likewise beveled, so as to cause a wedging engagement between the two, as most clearly shown in Fig. 5. The segmental tongues are furthermore provided at their outer edges with rounded beads 35, which are adapted, when the parts are in locking engagement, to fit in segmental grooves 36 formed on the inner faces of the segmental projections, as most clearly shown in Fig. 3.

Extending outwardly from each segmental projection 34 is a spring casing or container 37, preferably provided with a screw-cap so as to afford ready access to the spring when the cap is unscrewed. Within each casing or container is a coiled spring 38. The inner end of each spring bears against the head of a locking dog 39, the inner end of said dog being on a bevel (see Figs. 3 and 5). The dogs, when the locking heads are in locking engagement with each other, are adapted to engage the open-ended slots 33 of the segmental tongues 32. The dogs have connected thereto pivoted handles 40 which are pivotally mounted in recesses 41 for the accommodation thereof, the inner ends of said handles projecting through slots formed in the sides of the casings or containers 37, so as to engage the locking dogs. Whenever it is desired to release the locking dogs from engagement with the open-ended slots 33 the outer arms of the handles are pressed inwardly, and this will necessarily cause outward movement of the dogs against the contrary action of the springs.

The passage 42 through the locking head extends horizontally therethrough (see Fig. 8), and then at an angle, the angular extensions of the two passages 42 of the respective locking heads being alined, though held slightly apart by compressible rings 43. These rings are arranged to project resiliently laterally beyond the bordering edges of the angular extensions of the passages 42, so that the surfaces or the said bordering edges remain normally separated by the resilient pressure of the packing, thus pushing the rounded beads 35 of the segmental tongues forcibly but yieldingly into the grooves 36 and tending to prevent longitudinal separation of the locking heads. It is obvious that the compressible rings effectually prevent lateral leakage.

Each arc-shaped projection 34 at one end has extending therefrom a stop pin 44.

It will, of course, be understood that the segmental tongue 32 on each locking head is at the forward portion of said head, while the segmental or arc-shaped projection is 5 toward the rear end of the said locking head and spaced a distance from the main portion thereof so as to leave sufficient space for the entrance of the segmental tongue of the other locking head, in order to permit the 10 engagement of said segmental tongue with the groove of the segmental or arc-shaped projection.

In the use of the device, when it is desired to couple the locking heads, the segmental 15 tongue 32 of each head is passed into the space above the segmental or arc-shaped projection 34, the insertion being made from the side opposite to the side where the stop pins 44 are located. When so inserted the 20 rounded beads 35 of the tongues engage the grooves 36 of the projections 34 and ride in said grooves as the two locking heads are swung inwardly toward locking engagement. Also, as the segmental tongue 32 is 25 swung around on the segmental or arc-shaped projection there is a wedging action between the two, owing to the provision of the opposed beveled surfaces hereinbefore referred to. With the movement of the segmental tongue, as explained, it will contact 30 with the beveled end of the locking dog, and thereby raise said locking dog against the contrary action of the coiled spring 38, and permit of the open-ended slot of the segmental tongue coming into registration with 35 the end of said dog. The moment this registration takes place, the coiled spring will expand and force the dog into engagement with said slot. Of course, exactly the same 40 operation occurs with respect to the other dog, so that the parts are thereby locked together.

This particular form of locking means has most decided advantages, in that it prevents 45 any accidental separation due to turning or vibratory movement occasioned by jars or otherwise, while at the same time the longitudinal separation of the locking heads is permitted when the cars are subjected to 50 unusual or undue longitudinal stresses, as, for instance, from the uncoupling thereof, either designedly or accidentally. To make this advantage clearer, it will be noticed that the segmental tongues can only be 55 brought into engagement from the sides opposite to the sides where the stop pins 44 are located. When the tongues are turned inwardly sufficiently far to permit of the engagement of the locking dogs with the open-ended slots, it is obvious that if any turning 60 or vibration takes place, and which is sure to occur when the device is in use, the segmental tongues cannot work out of place in a direction opposite to the location of the 65 stop pins 44, for the reason that the high

portions of the beveled ends of the locking dogs will be in contact with the far walls of the slots, and thus prevent any movement in that direction. Again, it will be impossible for the tongues to work out of engagement 70 in the opposite direction, for the reason that the stop pins 44 will prevent this taking place. At the same time, however, there is nothing to prevent the longitudinal separation of the parts at any time, inasmuch as a longitudinal pull will readily release the rounded beads 35 from the grooves 36, and as the slots 33 are open-ended they, of course, will not interfere with this longitudinal separation. While couplings have heretofore 75 been provided which permit of longitudinal separation, they have been open to objection on the ground of the liability of accidental separation when the coupled members turn or are vibrated, no means having heretofore 80 been devised for preventing the same, in connection with means for permitting of longitudinal separation, as is the case with my invention.

Another important feature of the invention which has heretofore been alluded to and fully explained, is the employment of the inverted U-shaped packing for the swiveling joints, and the spring pressure device in connection therewith, whereby a free 95 turning at the joints is permitted, while yet a most efficient provision is made against leakage.

What I claim is:

1. In a train pipe coupling, the combination of sets of pipes adapted to be connected with the train pipes of coupled cars, each set consisting of a series of pipe sections connected with each other by joints adapted to permit a relative rotation, a terminal member for each set provided with a coupling head, said coupling head having a member adapted to fit within and to interlock interiorly with a part on the other coupling head to prevent longitudinal separation of the parts under ordinary strains, and said interlocking member being provided at its end edge with an open-ended longitudinally-extending slot, stop devices arranged on one side of each coupling head to prevent separation of said heads when swung or vibrated toward said side, and a locking dog carried by each coupling head, the dog of one coupling head adapted to engage the open-ended slot of the interlocking member of the other coupling head, when said heads are engaged one with the other, and each of said dogs provided with a beveled end, the bevel being in a direction to prevent separation of the coupling heads, when said heads are turned or vibrated in a direction away from the stop devices.

2. In a train pipe coupling, the combination of sets of pipes adapted to be connected with the train pipes of coupled cars, each set

consisting of a series of pipe sections connected with each other by joints adapted to permit a relative rotation, a terminal member for each set provided with a coupling head, said coupling head having a member adapted to interlock with a part on the other coupling head to prevent longitudinal separation of the parts under ordinary strains, and said interlocking member being provided at its end edge with an open-ended slot, stop devices arranged on one side of each coupling head to prevent separation of said heads when swung or vibrated toward said side, and a spring-actuated locking dog carried by each coupling head, the dog on one coupling head adapted by spring pressure to automatically engage the open-ended slot of the interlocking member of the other coupling head, when said heads are engaged one with the other, and each of said dogs provided with a beveled end, the bevel being in a direction to prevent separation of the coupling heads, when said heads are turned or vibrated in a direction away from the stop devices.

3. In a train pipe coupling, the combination of sets of pipes adapted to be connected with the train pipes of coupled cars, each set consisting of a series of pipe sections connected with each other by joints adapted to permit a relative rotation, a terminal member for each set provided with a coupling head, said coupling head having a member adapted to fit within and to interlock interiorly with a part on the other coupling head to prevent longitudinal separation of the parts under ordinary strains, and said interlocking member being provided at its end edge with an open ended longitudinally-extending slot, stop devices arranged on one side of each coupling head to prevent separation of said heads when swung or vibrated toward said side, a spring-actuated locking dog carried by each coupling head, the dog on one coupling head adapted by spring pressure to automatically engage the open-ended slot of the interlocking member of the other coupling head, when said heads are engaged one with the other, and each of said dogs provided with a beveled end, the bevel being in a direction to prevent separation of the coupling heads, when said heads are turned or vibrated in a direction away from the stop devices, and handles connected to the locking dogs and accessible from the exterior, said handles, when operated, adapted to release the dogs from locking engagement.

4. In a train pipe coupling, the combination of sets of pipes adapted to be connected

with the train pipes of coupled cars, each set consisting of a series of pipe sections connected with each other by joints adapted to permit a relative rotation, a terminal member for each set provided with a coupling head 65 adapted to fit the corresponding coupling head of the terminal member of the other set, and having tongued and grooved members adapted to be swung into mutual interlocking engagement with the corresponding 70 tongued and grooved members of the other set to prevent longitudinal separation of the heads under ordinary strains, each tongued projection being provided at its end edge with an open-ended longitudinally-extending 75 slot, stop devices arranged on one side of each coupling head to prevent separation of said heads when swung or vibrated toward said side, and a locking dog carried by each coupling head, the dog of one coupling head 80 adapted to engage the open-ended slot of the tongued projection of the other coupling head, when said heads are engaged one with the other, each of said dogs provided with a beveled end, the bevel being in a direction to 85 prevent separation of the coupling heads, when said heads are turned or vibrated in a direction away from the stop devices.

5. In a train pipe coupling, the combination of sets of pipes adapted to be connected 90 with the train pipes of coupled cars, each set consisting of a series of pipe sections connected with each other by joints adapted to permit a relative rotation, a terminal member for each set, the terminal members being provided with interlocking means, adapted to interlock with each other interiorly, when the terminal members are adjusted together each interlocking means provided with an open-ended longitudinally-extending slot, stop devices on one side of each coupling head to prevent separation of said heads when swung or vibrated toward said side, and a locking dog carried by each coupling head, the dog of one coupling head adapted to engage the open-ended slot of the interlocking means of the other coupling head, when said heads are engaged one with the other, and each of said dogs provided with a beveled end, the bevel being in a direction to prevent separation of the coupling heads, when said heads are turned or vibrated in a direction away from the stop devices.

In testimony whereof, I affix my signature, in presence of two witnesses.

WILLIAM F. CLASEN.
